UNITED STATES PATENT OFFICE.

JACOB ENGELHARDT, OF NEW YORK, N. Y.

FIRE-EXTINGUISHING APPARATUS.

Application filed February 14, 1925. Serial No. 9,080.

This invention relates to means whereby carbonic acid gas or the like, under pressure, may be employed for extinguishing fires, and my improvements are directed to a novel 5 device for the most highly efficient distributive delivering of the gas in and about the region of a fire, as well as to control means for the gas, actuatable through heat responsive means, so that the gas may flow to the delivery device. Also my invention comprises release means for self-closing doors and curtains actuatable by the gas release operating means, to permit the automatic closing operation of said doors and curtains.

10 Other features and advantages of my invention will hereinafter appear.

In the drawings:

Figure 1 is an interior view of a room or building, looking toward one wall thereof, 20 as equipped with my improved fire extinguishing means.

Fig. 2 is a section on the line 2—2 of Fig. 1.

Fig. 3 is an enlarged sectional elevation 25 of my improved gas distributory delivery device.

Fig. 4 is a section on the line 4—4 of Fig. 3.

Fig. 5 is a face view of an outwardly opening self-closing door, showing the release means therefor, and

Fig. 6 is a diagram of the switch circuits.

In the example of my invention illustrated in the accompanying drawings, wherein I 35 have shown the interior of a building or a room having the walls 1, roof or ceiling 2, window openings 3, 4 and door-ways 5, 6, let 7 indicate a gas distributing device, and 8 a pipe leading thereto from a suitable source 40 of supply, (not shown). I have not herein shown the supply source of carbonic acid gas, it being understood that the gas is contained under pressure in a suitable container or containers, located wherever installation 45 is most convenient, and the supply of the gas through the pipe 8 is controlled by a valve 9. It must also be understood that in a building having a number of rooms each 50 provided with one or more of the distributing devices, each supply pipe 8 may be provided with a valve 9.

The valve 9 is shown as provided with a controlling arm 10, that carries a weight 11, and is adapted to swing vertically to open 55 and close the valve. With said arm 10 in

the horizontal position shown in Fig. 2 the valve is closed. Normally this horizontal position is maintained by engaging means, such as a bolt 12, operable in guides 13, and lying beneath the weight, to support it. 60 But when said bolt is withdrawn, as by the means hereinafter described, then the weight, being released, will fall and thereby cause the valve to open.

As will presently appear, means are provided whereby the valve is caused to open as the result of a rise in temperature within the building or room equipped with my device, and then carbonic acid gas flows under pressure to the distributing device 7, which 70 latter is caused to rotate by the pressure of the entering gas, thereby dispersing the gas by throwing it rapidly in all radial directions.

Said device 7 comprises the fixed shell portion 75 14 and the revoluble shell portion 15, in interfitting relation to constitute a receptacle. In the example shown the portion 14 is secured, inverted, to the ceiling 2, and has a peripheral port 16 in communication with 80 pipe 8. A shaft 17 extends axially within device 7, being fixed at one end to the upper surface of portion 14, and projecting through a hole provided therefore in the base of portion 15. Revoluble upon shaft 85 17 is a sleeve 18, carrying radial vanes 19, and said sleeve is secured to the portion 15 as by a flange 20 that lies against the under surface thereof. A bushing 21 is placed upon the shaft 17, beneath the flange 20, 90 and a nut 22 threaded upon said shaft serves to complete the assembly, leaving the portion 15 free to rotate.

The arrangement of the vanes 19 is such that gas entering the device tangentially 95 within portion 14 will strike against said vanes, and since the vanes with the sleeve 18 form a part of the portion 14, rotation of the latter results. Extending radially from the wall of portion 14 are gas efflux 100 pipes 15^a, which are downwardly inclined and serve, by centrifugal action, to throw the gas in all radial directions at the high speed of rotation to which portion 15 is subjected by the entering gas pressure. 105

As retracting means for the bolt 12, to release weighted arm 10, thereby causing valve 9 to open. I provide a lever 23, pivoted at 24 to a support 25, one arm of said lever lying in the path of a weight 26 that is nor- 110

mally held in an elevated position by an electro-magnet 27, and, when the magnet is de-energized, is adapted to fall, to thereby rock the lever. A flexible connector 29, 5 passed over pulleys 30, 31, connects the other arm of the lever with the bolt 12, and operates to retract the bolt when the lever is rocked by the weight falling thereon.

The electro-magnet has two windings, one 10 of these windings being included in a circuit of fusible wire 32 which is strung about the walls and ceiling of the building or room and adapted to melt under the influence of a rise in temperature as by the breaking out 15 of a fire, thereby opening the circuit. If at such times the other circuit 33 is open the magnet will be de-energized and consequently weight 26 will drop.

The wiring includes a single point switch 20 34 adapted to co-act with the contacts I, II and III, a four point throw switch 35, a cut-out device 36, battery or other source of electrical energy 37, and a bell 38.

The wiring is so arranged that when 25 switch 34 is on contact I the circuit 33 will be open at cut-out 36. Consequently upon the fusing of circuit wire 32, magnet 27 will release weight 26, and the bell 28 will ring because the bell circuit closes at cut-out device 36 when circuit 32 is broken. If however the switch 34 is placed on contact II, 30 thereby circuit 33 is closed and energizes the magnet so that the weight will be held thereby when the fusible circuit is broken. Hence 35 the alarm only is given with this setting of switch 34, which is that desirable for daytime or when the room equipped with my improvements is occupied. An occupant of such room, realizing that a fire has started, 40 may then place the switch 34 on contact III, thereby causing circuit 33 to open through device 36, whereupon magnet 27 is de-energized and the weight 26 will drop.

The switch 34 should be located near to 45 or just outside an exit from the room so that the operator may leave the room when or before placing the switch.

Since my invention includes means, controlled by the falling of the weight, to permit self-closing doors and window curtains to close, it is desirable that said switch 34 should be outside the room, so that a person in the room may leave it before operating the switch.

Obviously the signal circuit may be carried beyond the building to a distant point to communicate the alarm.

In Fig. 1, I have shown the window openings 3, 4, each provided with a drop curtain 50 39 which may be of fire proof material, weighted at 40 and wound upon a roller 41, which latter is provided with an end hook 42 that is normally engaged by a bolt 43, operable in guide 44, to normally hold the curtain wound on its roller. Upon retrac-

tion of the bolt, releasing the hook, the curtain is drawn down by its weight, thereby covering the window opening. A cord 45, extended from connector 29, is passed over pulleys 46, to transmit the pull effect initiated by the rocking action of lever 23, and other cords 47, branching from cord 45, are passed over pulleys 48, to respectively engage the bolts 43, for their retraction.

Also in Fig. 1 I have shown an inwardly opening door 49, provided with a spring device 50 which urges it from the open to the closed position. Said door is normally held open by a bolt 51, slideable in guides 52, said bolt being engaged by the cord 45, to be retracted when said cord is pulled upon as previously described.

A fireproof, weighted curtain 53, wound on a roller 54 is mounted above the doorway, and is adapted to descend when the door is closed, to protect the latter. Extended from the roller 54 is a hook 55, normally engaged by a vertical bolt 56, which is held in its operative position by a spring 57, a cord 58 connecting said bolt with the floor. Door 49 is provided with an extended lug 59 that strikes the cord 58 as the door closes, thereby withdrawing bolt 56 to release hook 55, so that the curtain may be free to drop.

In Figs. 1 and 5 I have shown an outwardly opening door 60, having a spring 61 to urge it to its closed position, said door provided with an eyelet 62, adapted to receive a bolt 63, to hold said door normally open. A branch cord 64, passing over pulley 65, is extended from cord 45 and engages bolt 63, serving to withdraw said bolt for releasing the door.

From the foregoing description it will be apparent that the effect of the weight 26 falling upon and rocking the lever 23 is to cause carbonic acid gas to be violently whirled and thrown from device 7 in all radial directions, and simultaneously to release the spring held open doors and the latched curtains, which thereby automatically close the respective openings and protect the parts they are intended to cover.

Also it will be appreciated that the switch 60 115 may be set so that an alarm only will be given when a fire occurs, a manual operation of the switch then being necessary to cause the application of the gas and the closing operations aforesaid. Or, the switch may be so set that all the operations will be performed automatically when the rise in temperature melts the fusible circuit wire.

My experiments conducted for a number of years, have proven carbonic acid gas to be extremely efficient as a fire extinguisher. Furthermore, this gas is non-toxic and may within limits be breathed without danger to life or health. Nor will it injure goods of any kind with which it comes in contact.

Variations within the spirit and scope of my invention are equally comprehended by the foregoing disclosure.

I claim:

- 5 In apparatus of the character described, the combination with a room having windows and doors, a distributing device, a valved conduit for delivering fire-extinguishing material to said device, counter-
- 10 weighted mechanism associated with the valve of said conduit, a fusible electric circuit wire within said room, an electro-magnet in circuit therewith, a weight suspended by said magnet, a pivoted lever operable by said weight when released, a retractible member normally restraining said counter-

weighted mechanism against action, flexible means connecting said lever and retractible member and adapted to withdraw said member from engagement with said mechanism 20 on actuation of said lever to permit opening of said valve whereby to establish communication between said conduit and said distributing device, means for closing said doors and covering said windows; and release means 25 connecting said lever with said door and window closing means operable simultaneously with the establishment of communication between said conduit and said distributing device. 30

Executed this 10th day of February, 1925.
JACOB ENGELHARDT.
